UNITED STATES PATENT OFFICE.

WILLIAM FRANCIS THORNE, OF PASADENA, CALIFORNIA.

CARD GAME.

Application filed April 16, 1927. Serial No. 184,304.

This invention relates to new and useful improvements in card games and the principal object thereof is to provide an entertaining as well as educational game, the cards comprising the deck having indicia designating, or letters which conjointly spell a name, when the cards are assembled; certain of these cards having letters which when associated will spell the abbreviation of a name, and certain other of the cards having indicia designating different occupations followed in the particular community whose name is spelled by the foregoing arrangement of the cards.

Another important object of the invention resides in the provision of a deck of cards with which a great number of different games may be played, but particularly two games in which "books" are formed to constitute tricks of various scoring values.

Other objects and advantages of the invention will become apparent during the course of the following description.

In the accompanying drawing forming a part of the description and wherein like numerals are employed to designate like parts throughout the several views,

Figure 1 is a view showing diagrammatically all of the cards comprising the deck.

Figure 2 shows four of the minor or "Fan" cards each indicating a different suit.

Figure 3 shows four of the higher or "Chief" cards representing the four different suits, and

Figure 4 is a diagrammatic view of how the cards are arranged to form a border or "Grove" in playing one of the games.

Referring now more particularly to the drawing wherein I have specifically illustrated certain of the cards comprising the complete deck, so that the subject matter of the other cards will be perfectly clear, I will first describe all of the cards which comprise the deck. This deck of cards consists of sixty cards which are divided into four suits of fifteen cards each, named from high to low as Oranges indicated by the numeral 5 in Figure 2, Poppies by the numeral 6, Peppers by the numeral 7 and Palms by the numeral 8. The Orange and Poppy suits are of the same color, such as gold, while the Pepper and Palm suits are of a different color such as green, these colors being merely

arbitrary, but indicative of the color of the products represented.

As shown at the left side of Figure 1, the lower ten cards, viz: 1 to 10 or Ace to 10 of each suit are provided with indicia or individual letters 9 so that when the cards are arranged consecutively according to their numerical value, they will conjointly spell out a name. In this particular deck I have chosen the name "California" which comprises ten letters and in order that the "Fan" cards 1 to 10 will conjointly spell out the name "California" when arranged consecutively according to their numerical value, the card bearing the Ace or numeral 1 designation will contain thereover the letter C, the Deuce will bear the numeral 2 with the letter A thereover, the Trey will bear the numeral 3 with the letter L thereover, the four card the I, the five card an F, the six card an O, the seven card an R, the eight card an N, the nine card an I and the ten card an A as clearly shown at the left of Figure 1. Each card also bears an indication 10 of its particular suit in diagonally opposite corners at the margins as is common in decks of cards, it also being understood that the numerical value indication of the card as well as its respective letter 9 also appear at diagonally opposite corners of the cards above the suit indication 10. Each of these "Fan" cards from 1 to 10 also bear at the central portion thereof an enlarged indication 11 of its particular suit, as clearly shown in Figure 2, in this instance the indications being products of the State of California.

The "Chief" cards are indicated diagrammatically at the right side of Figure 1 and comprise twenty cards in two sets of ten cards each, and each set containing cards consecutively numbered 11 to 20 and bearing the letters comprising the word "California", the 11 card bearing the letter C, the 12 card the letter A, the 13 card the letter L and so on up to the 20 card which bears the letter A, the last letter of the name "California". These two sets of "Chief" cards are the face cards of the deck and each of these indicates a different occupation or recreation in the State of California. The first card to the left of Figure 3 indicates a face card of the Palm suit and contains a pictorial illustration in duplicate of an orange grower. The second

card in Figure 3 designates the 16 card of face card of the Pepper suit and contains a duplicate pictorial illustration of a driller and derrick. These two face cards of the 5 Palm and Pepper suits represent occupations in the State of California and also represent certain cards of the green "Chief" suits called Lords.

The third card shown in Figure 3 is the 10 eleven card of the Poppy or gold suit and contains a pictorial illustration in duplicate of a Bathing Girl or Mermaid, while the last card to the right of Figure 3 is the twenty 15 card of the Orange suit and contains a pictorial illustration in duplicate of a Movie Star. These two cards represent face cards of the Orange and Poppy suits or the gold 20 color set and the pictorial illustrations represent occupations or recreations, indulged in California.

From the foregoing it will be apparent that there are provided five face cards for each 25 suit, those of the Poppy and Palm suits being numbered consecutively from 11 to 15 and bearing respectively the letters C-A-L-I-F, whereas the Orange and Pepper suits each contain five face cards numbered consecutively from 16 to 20 and containing respectively the letters O-R-N-I-A as clearly indicated at 30 the right of Figure 1.

In order that it will be perfectly clear as to the indicia of the respective face cards I will list below all of the face cards according to the suit as well as their numerical value 35 and the individual letter each contains to cooperate in forming the word "California."

GREEN SUIT		LORDS	
	Palms	Pictured as	
40	C-11 Mariner	Spanish Sailor	
	A-12 Preacher	Mission Padre	
	L-13 Miner	Prospector	
	I-14 Engineer	Surveyor

	N-18 Artist	Painting West	
	I-19 Secretary	Office Girl	
55	A-20 Movie Star	Colleen Moore-Holywd.	

From the foregoing list it will be observed in Figure 3 that I have illustrated the fifteen of Palms, the sixteen of Peppers, the eleven 60 of Poppies and the twenty of Oranges in the respective order named, and that these cards also contain respectively the following letters F-O-C-A which are certain letters in the word "California." It will also be observed 65 from the foregoing list that the eleven to

fifteen cards inclusive of the Palm and Poppy face cards form the first half, C-A-L-I-F, of the name California, whereas the cards sixteen to twenty of the Pepper and Orange suits form the last half of the name California, 70 namely O-R-N-I-A, and consequently when the eleven to twenty cards in the Palm and Pepper suits are arranged consecutively according to their numerical values, they spell out the name California, and the same is true 75 of the face cards eleven to twenty of the Poppy and Orange suits which are called the Gold suit.

From Figure 1 it will also be clear that the first three cards, Ace, Deuce and Trey 80 of each "Fan" suit contains the letters C-A-L or an abbreviation of the State of California. Likewise the eleven, twelve and thirteen cards of the Palm and Poppy suits contain respectively, the letters C-A-L. 85

It will, therefore, be clear that there are six sets of letters making the word California or the abbreviation Cal.

The face cards are not merely equal rights cards, but are chivalrous cards, not only giving emoluments to the women but giving them pre-eminence in value in games. 90

Having thus described the individual cards comprising the deck, I will now outline briefly two games which may be played with the deck 95 of cards. Essentially the game consists of making "books" which score different values according to the suits to which they belong. The game I have called "California," is played as follows:

The forty "Fan" cards consisting of the cards numbered one (or Ace) to the ten in each suit are played in the form of an oblong or oval border on the card table with upper convex arch and lower concave arch facing the dealer (south), as shown in Figure 4 of the drawing, the upper arch containing as the game proceeds the letters C-A-L-I-F and the lower concave containing the letters O-R-N-I-A to make the complete word California. These cards will be played in ten tricks each composed of four cards of the same letters, thus the four C's or Ace cards of the four suits constitute one trick and the rest in like manner. It is not necessary to play the cards in the order they occur in the word, it being merely necessary to play the cards in its proper place in the oblong of the border where it belongs. Thus, you may play the L before the C or A if you wish, but it must be placed in the center of the upper arch of the border as the playing place is termed.

The balance of the face cards or "Chiefs", five of each suit, are played in suits making 125 four tricks of five cards each played in the "Garden" inside of the border shown in Figure 4. The dealer leads and may start any suit he desires in its place. The next players may build on his lead or start a new 130

trick so that there may be the entire fourteen tricks building simultaneously. The playing is in turn regardless of who takes the trick and the face value of the card in this particular game is of no importance, because the player of the last card in each trick (fourth card in border tricks and fifth card in "Garden" tricks) takes the trick when played. The cards may be taken in as soon as each book or trick is formed and the score taken after the hand has been played.

Each border trick counts five points; the Palm trick ten; Peppers twenty; Poppies thirty; and Oranges forty.

15 Another game which may be played with the deck of cards, I have termed "Orange Grove". In playing this game the twelve Orange cards numbered four to ten and sixteen to twenty are used to form the four corners of a square or "Grove", as it is called, on the card table as the game proceeds. Each corner consists of three of these Orange cards. One side of the Grove faces each of four players, but any number from three to six 25 may participate. In the center of each side line of the Grove is played another three card trick, the Ace, Deuce and Trey of each suit being played as separate tricks and are called Cal tricks because they bear the letters C-A-L, the abbreviation for California.

Neither the corner Orange Grove tricks or the line Cal tricks are played in the order of value because in all cases it is the last card played on a trick that takes it. Thus, 35 it will be seen that there are eight three card tricks in the boundary of the Grove.

The remaining thirty six cards (four to fifteen in Palms and Poppies and four to ten and sixteen to twenty in Peppers) are all 40 played inside of the Grove in three tricks of four cards each in Palms, Peppers and Poppies, making twelve tricks played in suits. This makes seventeen tricks in each hand played.

45 All of the cards are dealt at one time and the dealer leads any Orange suit card on a corner, or he may play any C or A or L card to start a center line trick, or one inside the garden to start an inside trick. The second player may play on the card led to build up that trick or he may start another trick with a different suit. The entire eight outside tricks may be building at once, but no more than three (one each of Palms, Peppers and 55 Poppies) may be building inside of the Grove at once. The tricks are taken from the board as soon as finished.

The scoring value of the tricks is as follows:

60 Each corner and each Cal trick counts 3; inside tricks, Palms 4; Peppers 6 and Poppies 8. Each trick over seven counts 5 points; bonus tricks in Lords, 6 out of 10 scores 5 points; seven out of ten scores ten points; 65 eight out of ten scores 25 points, nine out of

the possible ten, 50 points, and all ten scores 100 points. Bonus tricks with the Gold suit of Ladies, the score is doubled.

Bonus or courtesy scores may be earned by any player holding any number above five 70 of the ten cards which spell the name California.

Having thus described my invention, what I claim is:

1. A deck of cards comprising several suits 75 composed of two distinct color sets, each high suit of the respective color sets omitting a consecutively numbered group of cards, which group is contained in each low suit of the respective color sets.

2. A deck of cards comprising several suits divided into two color sets, each suit comprising cards numbered from one to ten and each low suit of the respective color sets being numbered eleven to fifteen and the two high 85 suits of the respective color sets being numbered from sixteen to twenty inclusive, cards of the two suits of the same color set being numbered consecutively from eleven to twenty and containing respectively the individual 90 letters of a name, said cards one to ten of each of the suits likewise containing respectively the individual letters forming the same name.

3. A deck of cards comprising a plurality 95 of suits composed of two distinct color sets, the cards of each suit containing letters to conjointly spell a complete name and in addition a part thereof when arranged in sequence, the suits of the respective color sets omitting certain lettered cards spelling part 100 of said name and adapted to be arranged in sequence with cards of another suit of the same color to conjointly complete the spelling of the same name.

4. A deck of cards comprising a plurality 105 of suits composed of two distinct color sets, each card of each suit containing an individual letter or letters which conjointly spell a complete name of a community when arranged in sequence, said suits of the respective 110 color sets containing face cards each indicating a different occupation of said community and containing an individual letter or letters and the face cards of the respective color sets omitting certain lettered cards which when 115 arranged in sequence with face cards of another suit of the same color conjointly spell the name of the same community.

5. A deck of cards comprising different 120 suits, one suit thereof omitting a card essential for a certain trick, said card having a suit color different from the suit omitting it and contained in another suit and adapted to be played in association with a card of the suit omitting it to constitute a trick.

6. A deck of cards comprising high and low suits, the cards of the low suits being consecutively numbered 1 to 15 inclusive and the cards of the high suits being consecutively numbered 1 to 10 inclusive and 16 to 130

20 inclusive, certain of the consecutively numbered cards of the low suits adapted to be consecutively arranged with the latter consecutively numbered groups of the high suits to constitute tricks.

5. 7. A deck of cards comprising suits each of which is composed of sets of different scoring values and each set including numbered cards, each containing a part of a name and adapted to conjointly spell a name when ar-

ranged in numerical sequence, each suit of the respective sets omitting certain cards which interrupt the numerical sequence and which are contained in each low suit of the respective sets and which when arranged in 15 numerical sequence with the cards of the low suits conjointly spell the same name.

In testimony whereof I have hereunto set my hand.

WILLIAM FRANCIS THORNE.
